UNITED STATES PATENT OFFICE.

WALDEMAR KOPS, OF NEW YORK, N. Y., ASSIGNOR TO NEMO CIRCLET COMPANY, INC.,
A CORPORATION OF NEW YORK.

BRASSIÈRE.

Application filed February 24, 1923. Serial No. 620,868.

To all whom it may concern:

Be it known that I, WALDEMAR KOPS, a citizen of the United States, residing in the borough of Manhattan, city, county, and 5 State of New York, have invented an Improvement in Brassières, of which the following is a specification.

This invention relates to a brassière, and like other garments of its general type is 10 adapted to be secured on the body of the wearer to overlie, confine and support the busts. In brassières as generally constructed, the tension applied at the front of the garment produces a more or less flat 15 front effect. Obviously the flattening of the busts in front causes a greater or less spread of the flesh at the sides, and the object of my invention is the provision of a garment in which the flat front effect will 20 be produced and adequate support provided for the spread of the flesh at the sides of the wearer, and also in the same garment to provide tension straps which are so placed as to be adapted to bear against and support 25 and thus control the diaphragm of the wearer.

To this end, in carrying out the invention, the garment made in accordance therewith is so constructed as to provide a front member 30 in which there is simultaneously produced a downward tension and lateral tension diverging to the lower front section of the garment to exert the necessary pressure for producing the flat front effect and to 35 provide for the support of the spread of the flesh at the sides of the body, and also suitable tension straps for producing a pressure against the diaphragm to control and support the same, as hereinbefore stated, and 40 as will be hereinafter more particularly described.

In the drawing:

Fig. 1 is a perspective view showing the 45 use of a brassière made in accordance with this invention.

Fig. 2 is a plan view of the inner side of the garment showing the same in a flattened position.

Fig. 3 is an enlarged outer elevation of 50 the lower front portion of the garment, and

Fig. 4 is a section on line 4—4, Fig. 3.

Referring to the drawing, the garment made in accordance with this invention preferably comprises a plurality of sections.

These include a front section 10, a side section 11, a side section 12 and a back section 13 in the right hand side of the garment, and a side section 14, a side section 15 and a back section 16 in the left hand side of the garment. The front section 10 is connected to the side section 11 along a line of stitching 17; the side section 11 is connected to the side section 12 along a line of stitching 18; the side section 12 is connected to the back section 13 along a line of stitching 19. Similarly on the other side of the garment the front section is connected to the side section 14 along a line of stitching 20; the side section 15 is connected to the side section 14 along a line of stitching 21, and the back section 16 is connected to the side section 15 along a line of stitching 22. At the back of the garment the free edge of the back section 13 is provided with a reinforcing strip 23 secured to which is a series of suitably spaced eyes 24. Along the free edge of the back section 16 there is provided a reinforcing strip 25 having secured thereto a corresponding series of hooks 26, each of which is adapted to engage one of the eyes 24. This garment is adapted to extend around the body from the front to the back and to be secured in position at the back by the hooks and eyes described. It will be understood, however, that the garment may be made to otherwise extend around the body and the parts thereof connected by any suitable attaching devices.

The rearward edge of the side member 11 extends from the upper edge of the garment to a point indicated at 27 along the line of stitching 18 by which these sections are connected, and at the forward edge of the side section 11 the same extends from the upper edge of the garment to a point indicated at 28, the lower portion of the side section 11 terminating in a tapered strap extending toward the lower central portion of the front section 10. Similarly on the other side of the garment the rear edge of the side section 14 extends from the top of the garment, that is the upper edge thereof to a point indicated at 30 along the line of stitching 21 connecting this section to the side section 15, and the forward edge of the side section 14 extends from the upper edge of the garment to a point indicated at 31 along the

line of stitching 20 by which the side section 14 is connected to the front section 10. The lower portion of the side section 14 terminates in a strap 32 which is the complement of the strap 29, and at their extremities these straps 29 and 32 are preferably connected to one another in any suitable manner as indicated at 33. Connected to and depending from the extremities of the straps 29 and 32 is a tape 34 carrying a hook 35 adjustable to position thereon, and at its extremity the hook 36. Connected centrally to the lower portion of the front member 10 is a reinforcing strip 37 in which a series of eyelets 38 is secured. It will be understood that the lower ends of the straps 29 and 32 are unattached to the lower portion of the front member and that in adjusting the garment to position the hook 35 is secured to a corset clasp or other device of an undergarment and the hook 36 engaged with either one of the eyes 38 whereby simultaneously a downward tension is exerted in the front member and lateral tensions applied through the straps 29 and 32 to the side sections 11 and 12 and 14 and 15 respectively, the former producing the flat front effect and the latter providing for the control of the flesh which is spread at the sides due to the flattening effect in the front. Also as illustrated, the lower front portion of the section 10 may be provided with a pad indicated at 39, the upper edge of which is indicated at 40. The pad may be attached to the section 10 in any suitable manner and may merely comprise a reinforcing section.

The garment also includes suitable tension straps for exerting a pressure against the diaphragm of the wearer. In the left hand side of the garment the tension strap includes a section 41 of inelastic material and a section 42 of elastic material. The lower edge of this tension strap completes the continuity of the lower edge of the garment, and the upper edge thereof is indicated at 43. The forward edge of this strap extends from the lower edge of the garment to a point indicated at 44 and is secured to the front section 10 and side section 11 by the same line of stitching 17 connecting these sections of the garment. The rear edge of the tension strap extends from the lower edge of the garment to a point indicated at 45 and is secured in position by the same line of stitching 18 that connects the side sections 11 and 12. Consequently, as will be apparent, the upper end of the forward edge of the tension strap overlies the lower portion of the side section 11 a predetermined distance and the upper end of the rear edge of the tension strap overlies the side section 11 a predetermined distance. Similarly in the right hand side of the garment the tension strap includes

a section 46 preferably made of inelastic material and a section 47 preferably made of elastic material. The lower edge of this tension strap completes the continuity of the lower edge of the garment at the front thereof, and the top edge of this strap is indicated at 48. The forward edge of this tension strap is connected to the garment along the same line of stitching by which the front section is connected to the side section 14, and the upper end of the forward edge terminates at a point indicated at 49 so that the tension strap at its forward end overlies the side section 14 for an appreciable distance. The rear edge of the tension strap extends from the lower edge of the garment to a point indicated at 50 and is connected along the same line of stitching which connects the side sections 14 and 15. The upper end of the rear edge of the tension strap terminates at a point indicated at 50 so that at the rear end thereof the tension strap overlies an appreciable portion of the side section 14.

As indicated in the drawing the garment may be provided with shoulder straps indicated at 51 and 52 which, at their extremities are preferably secured to the upper edge of the garment at the points between the front and side sections and between the back sections and the adjacent side sections. By reference to the drawing and particularly to Fig. 2, it will be clearly seen that the division line or line of stitches between the side sections 11 and 12 and the side sections 14 and 15 are at approximately the axillary line of the garment and that the diaphragm tension straps extend along the lower portion of the garment at their lower edges completing the continuity thereof, and from the front central section to approximately the axillary lines of the garment.

From the foregoing description, it will now be understood that in the garment described provision has been made for exerting simultaneously a downward tension in the front section of the garment to produce a corresponding inward pressure on the body of the wearer, and laterally extending downward tensions producing corresponding lateral pressures in the side section of the garment which are transmitted to the body of the wearer to produce the flat front effect and to provide for the support of the spread of the flesh at the sides due to the pressure at the front, and also to exert a variable pressure on the diaphragm to control and assist in supporting the same, which devices, in view of their overlapping structural features, coact with one another to produce the desired results. It will also be understood that as hereinbefore stated while the garment shown and described is closed at the front and the parts thereof connected at the back, the same may be otherwise com-

structed to carry out the purposes of the invention without departing from the nature and spirit thereof.

I claim as my invention:

- 5 1. In a brassière a body member having a front central section, side sections adjacent thereto, each side section having a strap continuation extending downwardly and forwardly, the said straps being connected at their extremities adjacent the lower edge of the brassière, and means connected to the extremities of the said straps to depend therefrom for coacting with the front central section to exert a straight downward tension in the front central section and laterally inclined downward tensions in the side sections of the brassière.
- 10 2. In a brassière, a body member having a front central section and adjacent side sections, the side sections including oppositely disposed downwardly inclined straps, the forward portions of the said side sections at the lower ends thereof terminating in the said straps which converge and are connected at their extremities adjacent the lower front central edge of the brassière, and a tape connected to and extending from the extremities of the said straps and provided with attachments for connection respectively to an under garment and the lower portions of the said central section of the brassière.
- 15 3. In a brassière a body member having a front central section, side sections adjacent thereto, the said side sections each having a strap continuation extending downwardly and forwardly with the said straps underlying the front central section and connected to one another at their extremities immediately below the front central section, and means connected to the extremities of the straps and the said front central section to exert a straight downward tension in the front central section and laterally inclined downward tensions in the side sections of the brassière.
- 20 4. In a brassière, a body member having a front central section and adjacent side sections, the side sections including oppositely disposed downwardly inclined straps, the forward portions of the said side sections at the lower ends thereof terminating in the said straps which underlie the front central section and are connected to one another at their extremities, and a tape connected to and extending from the extremities of the said straps and provided with attachment devices, one of which is adapted to be connected to an under garment and the other to one of a plurality of eyelets provided for this purpose in the lower portion of the said central section of the brassière.
- 25 5. In a brassière, a body member having a front central section and side sections extending from the front section to approximately the axillar lines of the garment, the said side sections including oppositely disposed downwardly inclined straps converging to the lower front central edge of the brassière, tension devices connected to the extremities of the said converging straps and coacting therewith to produce both a downward tension and laterally disposed side tensions in the said front central section of the brassière, and tension straps each including an elastic and an inelastic section extending from the front central section to approximately the axial line of the garment and each overlying a portion of the lower part of the corresponding side section of the brassière.
- 30 6. In a brassière, a body member having a front central section and adjacent side sections, the side sections including oppositely disposed downwardly inclined straps, the forward portions of the said side sections at the lower ends thereof terminating in the said straps which converge and are connected at their extremities adjacent the lower front central edge of the brassière, and a tape connected to and extending from the extremities of the said straps and provided with attachments for connection respectively to an under garment and the lower portions of the said central section of the brassière.
- 35 7. In a brassière, a body member having a front central section and adjacent side sections, the side sections including oppositely disposed downwardly inclined straps, the forward portions of the said side sections at the lower ends thereof terminating in the said straps which underlie the front central section and are connected to one another at their extremities, and a tape connected to and extending from the extremities of the said straps and provided with attachment devices, one of which is adapted to be connected to an under garment and the other to one of a plurality of eyelets provided for this purpose in the lower portion of the said central section of the brassière.
- 40 8. In a brassière, a body member having a front central section and side sections extending from the front section to approximately the axillar lines of the garment, the said side sections including oppositely disposed downwardly inclined straps converging to the lower front central edge of the brassière, tension devices connected to the extremities of the said converging straps and coacting therewith to produce both a downward tension and laterally disposed side tensions in the said front central section of the brassière, and tension straps each including an elastic and an inelastic section extending from the front central section to approximately the axial line of the garment and each overlying a portion of the lower part of the corresponding side section of the brassière.

Signed by me this 26th day of January, 1923.

WALDEMAR KOPS.
